COMBINED CHRISTMAS TREE ORNAMENT AND LIGHT

Maya Bendzin, Phoenixville, Pa.

Application March 21, 1955, Serial No. 35,115

Term of patent 14 years

(Cl. D29—1)

The dominant features of the design reside in the portions shown in full lines.

I claim:

The ornamental design for a combined Christmas tree ornament and light, as shown and described.
